PRINTING TELEGRAPH APPARATUS

Walter J. Zenner, Des Plaines, Ill., assignor to
 Teletype Corporation, Chicago, Ill., a corpora-
 tion of Delaware

Application May 25, 1948, Serial No. 29,059

18 Claims. (Cl. 178—34)

1

This invention pertains to printing telegraph apparatus, and particularly to a type wheel printer.

The primary object of the present invention is to provide a telegraph recorder of compact construction wherein all of the functions incident to the printing of a character are completed within a single cycle of rotation of the operating and selecting shaft.

Another object of the invention is to provide a printer wherein the selection and printing of a character is performed within the same cycle.

The printer according to the present invention is of the class of printers shown in the W. J. Zenner Patent No. 2,279,609 issued April 14, 1942, wherein a ribbed drum, or cylinder, has been substituted by an assembly of stop discs rotatable as a unit and having teeth on their peripheries arranged to cooperate with a signal controlled escapement member. As distinguished from the structure according to the Zenner patent, the assembly of discs in the structure according to the present invention, is movable longitudinally along with the shaft on which the type wheel is mounted, whereas in the structure according to the Zenner patent, the cylinder is not movable. Furthermore, in the structure according to the present invention, the escapement member is given only a motion of oscillation instead of both rotation and translation as is the case in the structure according to said patent. Moreover, with the printer according to the present invention, a 2-row type wheel is provided, together with a novel shift mechanism controlled by the stop discs.

Briefly, the structure according to the present invention, includes a pair of motor driven shafts, one of which carries a type wheel and a group of toothed wheels or stop discs, and the other of which carries selecting and operating cams. A selector magnet, the armature of which is actuated cyclically by a selector cam and is held when the magnet is energized, by certain signal impulses, controls an escapement member comprising a pair of pawl latches which straddle the group of stop discs in escapement fashion. The assembly or group of discs is movable along the supporting shaft while the escapement member is given only a motion of oscillation, as previously-mentioned. The stop elements on the discs are progressively doubled in number. Each group of stop elements lies in its individual plane. The individual fingers or projections on the periphery of the stop discs are placed equidistant with respect to each other, and the groups of

2

stop fingers or elements are arranged in the order of one, two, four, eight, and sixteen teeth for controlling the position of the type wheel in accordance with signal impulses received by a selector magnet. These stop elements or teeth are assembled in relation to each other so that they will form 32 equidistant steps.

For a more complete understanding of the present invention reference may be had to the following detailed description, taken in connection with the accompanying drawings, in which,

Fig. 1 is a plan view of the printing telegraph machine according to the present invention;

Fig. 2 is a sectional view taken substantially in line with 2—2 of Fig. 1;

Fig. 3 is a representation in exploded form of the stop discs according to the present invention;

Fig. 4 is a fragmental view disclosing the structure comprising the shift mechanism of the present printer;

Fig. 5 is a front elevational view, partially in section, of the printer according to the present invention; and

Fig. 6 is a fragmental plan view of a portion of the printer according to the present invention.

Referring now to the drawings and in particular to Fig. 1 thereof, reference numeral 11 represents the base of a combined keyboard transmitter indicated generally by reference numeral 12 and a telegraph receiver 13. The keyboard transmitter 12 is preferably of the type forming the subject matter of the copending application for patent of W. J. Zenner, Serial No. 778,005, filed October 4, 1947, now Patent No. 2,534,494 of December 19, 1950, however, any of the well known keyboard transmitters can be used. It is the receiver 13 which forms the subject matter of this invention.

A standard electric motor 14, suitably secured to the base 11, has a worm gear 16 secured to its shaft (not shown) which drives a gear 17. The gear 17 is secured to a shaft 18 which is journalled in a pair of brackets 19 and 21. The gear 17 meshes with an idler gear 22 which is rotatably secured to the bracket 19, and the idler gear 22 meshes with a gear 23 secured to a hollow sleeve 24. A gear 26 secured to the shaft 18 supplies power to a transmitter mechanism 27 of the keyboard transmitter 12.

The shaft 18 carries a drive disc 28 which is urged suitably towards another cooperating drive disc 29, the disc 29 being fixed to the shaft 18 and the disc 28 being translatable thereon. Between the drive discs 28 and 29 there are the usual felt washers 31 which are in frictional en-

gagement with a driven disc 32. When the driven disc 32 is held in a stopped position the drive discs 28 and 29 rotate relative thereto, however, when the driven disc 32 is released it is rotated with the drive discs due to the frictional engagement afforded by the felt washers 31. A cam sleeve 33 is rotatable on the shaft 18 and carries an arm 34 which is adjustable rotatably relative to the cam sleeve and rests between a pair of lugs 36 on the driven disc 32, to afford a driving connection between the sleeve 33 and driven disc 32.

Referring to Fig. 2, a selector magnet 37 is rigidly secured to the base 11 and has a cooperating armature 38 which is mounted pivotally on a shaft 39. The mechanism for releasing the cam sleeve 33 includes a lever 41 and a clutch trip off lever 42. The lever 41 is mounted pivotally on the shaft 39 and its pivotal movement is controlled by the armature 38. A spring 43, fastened at one end to a lug 44 on the lever 41, is fastened at its other end to a lug 46 on an armature assist lever 47 and urges the lever 44 counterclockwise about its pivot shaft 39. The armature assist lever 47 is an integral part of the armature 38. An adjusting bolt 48 is provided for positioning the lever 41 relative to the armature 38. The clutch trip off lever 42 is mounted pivotally on a shaft 45 and has a shoulder 49 for cooperating with the arm 34 to block rotation of the driven disc 32 with the driving discs 28 and 29. A spring 51 urges the clutch trip off lever 42 counterclockwise towards an eccentric adjusting bolt 52 in order to align the shoulder 49 in the path of the arm 34. A foot 53 of the clutch trip off lever 42 cooperates with the lever 41 whereby clockwise movement of the clutch trip off lever 42 is blocked when the armature 38 is pulled up due to energization of the magnet 37. When the magnet 37 is de-energized a spring 54 moves the armature 38 clockwise (Fig. 2) to the dotted position 56 thereof which causes the lever 41 to be moved to its dotted position 57 at which time the arm 34 is permitted to pivot the clutch trip off lever 42 clockwise against the action of the spring 51. The foot 53 on the clutch trip off lever 42 moves free of the lever 41 until the arm 34 overrides the shoulder 49 permitting the spring 51 to return the clutch trip off lever 42 to its normal position.

The cam sleeve 33 has a plurality of cams rotatable therewith among which is an armature assist cam 58 which has a plurality of high portions 59 spaced around its periphery. A cam follower 61 on the armature assist lever 47 cooperates with the armature assist cam 58 to move the armature towards the selector magnet 37 immediately prior to the receipt of signal impulses by the magnet 37, which makes it possible to control the armature by much weaker signal impulses than is necessary when the armature must be pulled up entirely by the magnetic force of the energized magnet.

A cam 62 cooperates with a follower 63 on a lever 64. The lever 64 is mounted pivotally on a bolt 66 secured to the bracket 21 and is held in spaced position thereon by a spacer sleeve 67. A spring 68 urges the lever 64 counterclockwise (Fig. 2) whereby the follower 63 is urged continuously towards the cam 62. An extended portion 69 of the lever 64 cooperates with the upper extremity of a lever 71 which is secured to the armature assist lever 47 by bolts 72.

The lever 64 has a pair of operating surfaces 73 and 74 for controlling respectively a stop pawl

76 and a holding pawl 77. The pawls 76 and 77 are mounted pivotally on the bolt 66 and are continuously urged towards one another by a spring 78. The pawls 76 and 77 are fitted respectively with individual adjusting bolts 81 and 82 which cooperate respectively with the operating surfaces 73 and 74 on the lever 64. The timing between the armature assist cam 58 and the cam 62 is such that the high portions 59 of the armature assist cam 58 urge the armature assist lever 47 counterclockwise (Fig. 2) while the lever 64 is pivoted clockwise by the high portions of the cam 62. The follower 61 on the armature assist lever 47 drops to a low part of the armature assist cam 58 just prior to the presentation of the corresponding low part of the cam 62 to the follower 63. If the selector magnet 37 is not energized due to the receipt of a spacing signal impulse the armature 38 falls back due to the urging of the spring 54 to thereby move the lever 41 beneath the extended portion 69 which prevents the follower 63 from dropping to the low portion of the cam 62. If the selector magnet 37 is energized due to the receipt of a marking signal impulse the armature 38 is retained in its pulled up position and subsequently, when the follower 63 drops to one of the low parts of the cam 62, the extended portion 69 of the lever 64 is permitted to be urged downwardly behind the lever 71. The lever 64 is thereby pivoted counterclockwise to raise the pawls 76 and 77.

The hollow sleeve 24 is journaled in the bracket 19, and carried rotatably within the sleeve 24 is a shaft 86 which is longitudinally movable and rotatable relative to the sleeve 24. A sleeve 87 is rotatable within a supporting journal 88 and the shaft 86 is slidable within the sleeve 87. The shaft 86 is also journaled for rotational and slidable movement in the bracket 21. The sleeve 24 carries a pair of friction discs 89 which form the drive member of a friction clutch 91. The friction discs 89 are adapted to drive a disc 92 which is rotatable about the sleeve 24, the driving connection between the drive discs 89 and the driven disc 92 being accomplished through the medium of the usual felt washers 93. The disc assembly is urged together by a compression spring 94 which abuts a nut 96 on the sleeve 24. The sleeve 87 carries a pair of arms 97 which engage notches in the periphery of the disc 92 to afford a means of driving the sleeve 87.

The shaft 86 has a stop unit or projection assembly 101 rigidly secured thereto which consists of a plurality of toothed elements or ratchet members 102-107, shown in detail in Fig. 3. An arm 111 secured to the sleeve 87 extends along the shaft 86 through the apertures 112 and 113 in the ratchet members 107 and 106 respectively and is adapted to impart rotation to the projection assembly 101 while the projection assembly 101 is moved longitudinally with the shaft by means to be hereinafter described.

A shaft 112 is mounted securely in the bracket 21. A member 113 is secured to a sleeve 114 which is slidable on the shaft 112. The opposite end of the member 113 has a semicircular notch (not shown) with which the grooved portion of a collar 116 cooperates. The collar 116 is secured to the shaft 86 and has a ratchet 117 on one side thereof. A bell crank 120 having a pawl (not shown) is urged continuously into cooperation with the ratchet 117 by a spring 125 and prevents any backward bounce of the projection assembly 101 when it is stopped.

The lower depending portion (not shown) of

the member 113 is bent in the form of a U to receive a knobbed portion 118 (Fig. 6) of a lever 119 which is pivoted on the bolt 121. A member 122 is also pivoted on the bolt 121 and has a cam follower 123 which, by means of a spring 126, is held continuously in contact with a cam 124 secured to and rotatable with the cam sleeve 33. An upturned portion of the lever 119 is fastened to a spring 127 which is fastened at its other end to the member 122, the lever 119 thereby being maintained in contact with an adjusting eccentric 128 continuously. By the use of the spring 127 there is provided a yield for the lever 119, so that if for any reason longitudinal movement of the shaft 86 is restrained, the spring 127 will yield. As the cam 124 rotates with the cam sleeve 33, the shaft 86 and the various mechanisms attached thereto are moved longitudinally as the lever 119 pivots about the bolt 121.

When the circuit through the selector magnet 37 is closed, but at a time when no signals are being received, the magnet 37 is energized continuously. At this time the sleeve 33 is prevented from rotating due to the blocking of the clutch trip off lever 42 by the lever 41. Also at this time the shaft 86 and projection assembly 101 are in the positions thereof as shown in Fig. 6. Rotation of the projection assembly 101 is prevented due to the engagement of the ratchet member 102 with the stop pawl 76. When a signal is received the first impulse is a start or spacing impulse which causes the selector magnet 37 to be de-energized momentarily which in turn permits the armature 38 and lever 41 to pivot clockwise (Fig. 2) thereby releasing the cam sleeve 33 for rotation. Assuming that the first signal impulse of the incoming signal is a marking (current) impulse, the lever 64 pivots counterclockwise (Fig. 2), the extended portion 69 dropping behind the lever 71. As the lever 64 pivots in this manner the pawl 76 is raised, which releases the ratchet member 102 from engagement with the pawl 76 to thereby permit the drive discs 89 to impart rotary motion to the driven disc 92 which in turn cause the projection assembly to rotate. As the pawl 76 is raised the pawl 77 is likewise raised into the path of the rotating ratchet member 102 to momentarily stop the rotation of the projection assembly 101. Thereafter as the follower 63 on the lever 64 is raised by the next subsequent high portion on the cam 62, the lever 64 is pivoted to cause the pawl 77 to release the ratchet member 102 so that the projection assembly 101 continues to rotate. While the projection assembly 101 is rotating in this manner the cam 124 rotates with the cam sleeve 33 and because of this, by the time the lever 64 is raised to allow the pawl 77 to release the ratchet member 102, the projection assembly 101 is moved longitudinally with the shaft 86 so that the ratchet member 103 engages the pawl 76. The pitch of the cam 124 is such that the projection assembly 101 is moved longitudinally with the shaft 86 so that the stop pawl 76 is at all times aligned with the ratchet member 103—107 which corresponds to the particular impulse being received. It should be noted that the projection assembly 101 has completed a half revolution from its stop position when the ratchet member 103 engages the stop pawl 76. As the lever 64 is pivoted in response to the next marking impulse of the incoming signal the projection assembly rotates a quarter revolution from the point of disengagement of the pawl 76 from the ratchet member 103 until the pawl 77 engages

one of the projections on the ratchet member 104. The rotational distance the projection assembly 101 travels when the pawls 76 and 77 are pivoted due to the receipt of marking impulses is one eighth of a revolution when the ratchet member 104 is released, one sixteenth of a revolution when the ratchet member 105 is released, and one thirty-second of a revolution when the ratchet member 106 is released. Remembering that a spacing impulse prevents rotation of the projection assembly 101 due to the fact that the pawl 76 does not release the projection it engages at that time, it is readily apparent that the projection assembly 101 may be rotated to any one of thirty-two positions when the five marking or spacing impulses are permuted in all possible combinations.

The pawl 77 is urged towards engagement with the projection assembly 101 each time the pawl 76 releases the projection assembly 101 for rotation. The function of the pawl 77 is to engage one of the teeth on the projection assembly to stop the rotation of the assembly momentarily to prevent the projection on the ratchet member immediately subsequent to the ratchet member which has just been released, from overriding or rotating to the point where it cannot be engaged by the pawl 77. Due to the fact that the normal amount of rotation of the projection assembly 101 must be sufficient to rotate the projection assembly a half revolution during the first signal-impulse interval and a quarter revolution during the second impulse interval, it is apparent that several of the projections on the ratchet members 106 and 107 would rotate beyond the stop pawl 76 if it were not for the action of the pawl 77 in preventing it.

In the operation of this receiver there is necessarily some slippage between the clutch discs 92 and 93 so that there is not an instantaneous rotation of the projection assembly 101 when it is released by the stop pawl 76. The ratio of the diameters of the gears 17 and 23 is roughly three and one-half to one. The shaft 18 and consequently the cam 62 makes one revolution during a complete signal and approximately one seventh of a revolution during the receipt of a single impulse of a signal. Assuming that the first signal impulse is a marking signal, it is necessary that the projection assembly complete at least a half revolution after the ratchet member 102 is released by the pawl 76. If the projection assembly 101 is not rotated sufficiently and if the second signal impulse is marking, the projection on the ratchet member 102 is engaged by the pawl 77 which is pivoted counterclockwise in response to the second marking signal and therefore the projection on the ratchet member 103 is stopped by the pawl 76 when the pawl 77 releases the ratchet member 102. Under these conditions the projection assembly 101 rotates only half a revolution instead of three quarters of a revolution in response to the first two marking impulses of the signal. Therefore provision is made to overcome this undesirable result due to the slippage referred to above.

The pawl 77 is provided with an extended arm 131 having an upturned foot 132 thereon. A spiral cam arm or deflector 133 is secured to the shaft 86 and is rotatable therewith. The spiral cam arm or deflector 133 is adapted to cooperate with the foot 132 in order to cam the pawl 77 from engagement with the projection assembly. When there is slippage between the discs 93 and 92 the projection assembly may not commence

rotation until the discs 93 have made as much as one sixth or more of a revolution. In such case in the absence of deflector 133 and cooperating foot 132 the pawl 77 would stop the projection on the ratchet member 102 when the pawl 77 is permitted to move with the lever 64 in response to a second marking impulse. But even though the projection assembly 101 has not moved rotatably a half revolution in response to the first marking signal, it will have moved transversely or longitudinally with the shaft 86 due to the continuous rotation of the cam 124. When the projection assembly 101 has moved in this manner the deflector 133 engages the foot 132 to cam the pawl 77 from engagement with any of the projections on the projection assembly 101 and because of this the ratchet member 102 is not stopped by the pawl 77 when released as a result of the second marking impulse. The deflector 133 releases the foot 132 when the projection on the ratchet member 102 passes the pawl 77. As the high part of the cam 62 corresponding to the third signal impulse causes the pawl 76 to be moved to its lower or blocking position the projection on the ratchet 104 engages the stop pawl 76. Therefore the projection assembly 101 will have moved three quarters of a revolution even though there is slippage between the clutch discs 93 and 92.

A type wheel 136 is secured to a sleeve 137 which is mounted on the shaft 86 and movable longitudinally thereon. The sleeve 137 is also rotatable on the shaft 86 but only for purposes of adjusting rotatably the type wheel 136. A plate 138, secured to the shaft 86, is adjustable rotatably thereon and has an arm 139 which extends through an aperture 141 in the type wheel 136. A second plate 142 is rigidly secured to the shaft 86 by a nut 143 and has a pair of circular slots 144 therein. A pair of bolts 146 extends through the slots 144 into a pair of screw threaded apertures (not shown) in the plate 138 to facilitate rotary adjustment of the type wheel 136. The arm 139 has a compression spring 140 suitably secured thereto which abuts a washer 145 to urge the type wheel 136 longitudinally along the shaft 86.

Mounted slidably and rotatably on the shaft 112 is a bracket 147 which carries a felt roller 148 for holding a supply of ink and a rubber inking roller 149 which engages the type wheel 136 to maintain the type wheel 136 in a printing condition. The bracket 147 has an arm 151 which rides in a slot 152 in a collar 153 on the sleeve 137 to maintain the rollers 148 and 149 in alignment with the type wheel 136. The arm 151 is maintained within the slot 152 by a spring 154.

In order to permit the receiver comprising this invention to be used on circuits employing page printers and also to increase the number of characters which can be printed the receiver is provided with a shift mechanism which is capable of controlling the longitudinal positionment of the type wheel 136 relative to the shaft 86. The type wheel 136 has two rows of characters and, when in printing position, occupies the unshift position when it assumes the solid line position shown in Fig. 4 and is in the shift position when occupying dotted position 156 as is also shown in Fig. 4. The shift and unshift mechanism is shown in Figs. 4 and 6. A bracket 157 is secured to the bracket 21. A shift and unshift lever 161 is mounted pivotally on the bracket 157 by a bolt 162 and is urged in a clockwise direction by a spring 163. The shift and unshift lever 161 has an arm 164 having a latch or foot 166 thereon

and is movable to either the solid line position thereof as shown or the dotted position 167 as shown in Fig. 4. The shift and unshift lever 161 also has an arm 168 having an upturned foot 169 which cooperates with a shoulder 172 on a bell crank lever 171. The bell crank lever 171 is mounted pivotally on a bolt 173 and is adjustable by means of an eccentric 174. The bell crank lever 171 is biased clockwise about the bolt 173 by a spring 176 suitably secured to the bracket 157. The foot 166 on the arm 164 cooperates with the collar 153 to control the longitudinal positionment of the type wheel 136 on the shaft 86 in a manner such that as the shaft 86 is moved to bring the type wheel 136 into printing position due to the action of the cam 124, the foot 166 engages the collar 153 and holds the type wheel 136 in unshift position against the action of the spring 140 when the arm 164 is in its solid line position (Fig. 4). When the arm 164 is in its dotted line position (Fig. 4) the spring 140 is permitted to expand whereby the type wheel 136 moves to unshift position as represented by the dotted position 156 when the shaft 86 is moved to printing position. When the type wheel 136 is in shift position a first row of type faces is in printing position and when the type wheel is in unshift position a second row of type faces is in printing position.

A U-shaped bracket 177 is secured suitably to the bracket 21 and carries a pair of longitudinally slidable pins 178 and 179, the pin 178 being the unshift pin and the pin 179 being the shift pin. It is apparent that when the shift pin 179 is moved forward it engages the shift and unshift lever 161 to pivot it against the action of the spring 163 thereby moving the arm 164 to its dotted position 167 (Fig. 4) or shift position. When the lever 161 is moved in this manner the foot 169 is moved counterclockwise which permit the spring 176 to pivot the bell crank 171 clockwise so that the shoulder 172 latches the foot 169 thereby retaining the shift and unshift lever 161 in its shift position. When the shift and unshift lever 161 is in its shift position a forward movement of the unshift pin 178 causes it to engage and pivot the bell crank 171 against the action of the spring 176 thereby releasing the shoulder 172 from latching engagement with the foot 169 which permits the spring 163 to move the shift and unshift lever 161 to its unshift position.

When an unshift or letters signal, consisting of five marking impulses, is received by the selector magnet 37, the projection assembly 101 is rotated in response thereto through thirty-one of its thirty-two different stop positions and also is advanced longitudinally, carrying with it the type wheel 136, to printing position. When the projection assembly 101 is moved in this manner the projection on the ratchet member 102 is aligned with and engages the unshift pin 178 to move it forward which in turn results in the retention of the type wheel 136 in unshift position. When a shift or figures signal, which consists of all marking impulses except number three which is a spacing impulse, the projection assembly 101 is rotated through twenty-seven of its thirty-two different stop positions which brings the projection on the ratchet member 102 into alignment with the shift pin 179. The longitudinal movement of the projection assembly 101, due to the action of the cam 124, then causes the shift pin 179 to be moved forward to permit the spring 140 to

move the type wheel 136 to shift position as represented by the numeral 156 (Fig. 4).

A print hammer cam 181 is secured to the cam sleeve 33 and is rotatable therewith. A member 182, mounted pivotally on a bolt 183, has a follower 184 which rides the cam 181 continuously due to the urging of a spring 185 suitably secured to the receiver frame. A print hammer lever 187 is mounted pivotally on the bolt 183 and has a print hammer 188 secured thereto which cooperates with the type wheel 136 to print the selected character on a tape (not shown) carried by a tape chute 189. The tape chute 189 has a suitable aperture 190 which permits the print hammer 188 to force the tape against the type wheel 136. The member 182 carries an adjusting screw 191 for adjusting the position of the print hammer lever 187 relative thereto. The print hammer lever 187 yieldably follows the pivotal movement of the member 182 and is held normally against the adjusting screw 191 by a tension spring 192 secured to the member 182. Where the cam sleeve 33 is released for rotation the cam 181 urges the follower 184 slowly to the left (Fig. 5) which takes place while the position of the type wheel 136 is being determined according to the signal received by the selector magnet 37. When the type wheel 136 is ultimately positioned, the cam 181 continues to advance until the follower 184 drops to the low part of the cam 181, whereupon the spring 185 contracts to move the member 182 clockwise which raises the print hammer lever 187 until the print hammer strikes the tape to move it against the type wheel 136 in order to print the selected character thereon.

Means is also provided for advancing the tape in the tape chute 189 in order to produce a space between the characters printed on the tape. A bolt 193 is secured to the bracket 21 and supports a sleeve 194 which is rotatable freely therearound. A tape feed wheel 196 at one end of the sleeve 194 and having serrations on its periphery suitable for frictionally engaging the tape, is positioned directly above the tape chute 189. A ratchet wheel 197 is affixed to the other end of the sleeve 194 for imparting rotation to the tape feed wheel 196. A pawl 198 which cooperates with the ratchet wheel 197 to impart rotation thereto is secured pivotally to an upstanding portion 199 of the member 182 by means of a bolt 201. A spring 202 urges the pawl 198 clockwise about the bolt 201 to thereby maintain the pawl 198 and the ratchet wheel 197 in continuous engagement. When the member 182 is pivoted counterclockwise due to the action of the cam 181 cooperating with the follower 184 the pawl 198 is moved to the left (Fig. 5) to advance the ratchet wheel 197 a step, to cause, in turn, the advancement of the tape feed wheel 196.

A pressure roller 203 is secured rotatably to the bell crank 204 by a bolt 206. The bell crank 204 is mounted pivotally by a bolt 207 and is urged in a counterclockwise direction by a spring 208 to cause the roller 203, which protrudes through an aperture in the tape chute 189, to maintain the tape in continuous frictional engagement with the tape feed wheel 196. The bell crank 204 is provided with a handle 209 which, when depressed manually against the urging of the spring 208, causes the roller 203 to be withdrawn downwardly thus permitting the manual feeding of tape through the tape chute 189.

Having thus described the apparatus embodied in the invention it is felt that a brief description

of the sequence of operations of the receiver will be helpful for a more complete understanding of the invention.

Incoming signals are received by the selector magnet 37 which, when de-energized by the incoming start signal, permits rotation of the sleeve 33. The receipt of the subsequent permutation of five marking and spacing signals controls the escapement mechanism, comprising the lever 64 and pawls 76 and 77. The cam 124, which rotates with the sleeve 33 and causes the longitudinal advancement of the projection assembly 101, cooperates with the escapement mechanism to control the rotational movement of the projection assembly in accordance with the signal received by the selector magnet 37. The rotational movement of the projection assembly 101 causes the type wheel 136 to be moved to the corresponding position and the longitudinal movement of the projection assembly 101 results in a movement of the type wheel 136 to printing position. At the same time that the type wheel 136 is being positioned selectively the tape is being advanced to provide a space between the characters printed thereon. Thereafter the follower 184 slips off the high part of the cam 181 permitting the print hammer 188 to strike the tape and move it against the character selected on the type wheel 136. Very shortly thereafter the following 123 slips off the high portion of the cam 124 thereby permitting the spring 126 to return the projection assembly 101 and type wheel 136 longitudinally to inoperative position. The continuously rotating clutch disc 92 then imparts the necessary rotation to the sleeve 87 to return the projection assembly 101 to its stop position with the projection on the ratchet member 102 against the stop pawl 76. The apparatus is then in condition for the receipt of another signal by the selector magnet 37.

It is to be expressly understood that various changes and modifications may be made in the invention without departing from the spirit or scope thereof.

What is claimed is:

1. In a selector, a shaft rotatably and translatable movable to any one of a plurality of character stop positions, means for rotating said shaft, a projection assembly comprising a plurality of toothed members carried by said shaft, escapement means cooperating with said projection assembly for arresting rotational movement of said shaft, and means for imparting translational movement to said shaft to thereby permit said escapement means to engage successive ones of said toothed members to determine the stop position of said shaft.

2. In a selector, a shaft rotatably and translatable movable to any one of a plurality of character stop positions, means for rotating said shaft, a projection assembly carried by said shaft, said projection assembly comprising a plurality of toothed members arranged successively along said shaft, an escapement mechanism cooperating with said projection assembly for arresting rotational movement of said shaft, and means for imparting translational movement to said shaft whereby said escapement mechanism cooperates with successive ones of said toothed members to determine the stop position of said shaft.

3. In a telegraph receiver, a rotatable type wheel provided with a plurality of characters, means having a series of elements thereon arranged in a plurality of planes for controlling the rotation of said type wheel, means for imparting

11

rotational and translational movements to said first recited means, stop means cooperable with said elements during the rotational and translational movements of said first recited means for controlling said first recited means, and a signal responsive means for controlling said stop means.

4. In a telegraph printer, a rotatable and translatable shaft, a type wheel carried by said shaft and movable therewith, means carried by said shaft having a plurality of rows of projections thereon, an escapement mechanism responsive to signal impulses for cooperating with said projections to control the rotation of said shaft, and means for effecting translational movement of said shaft to permit said escapement mechanism to cooperate with successive rows of said projections, said type wheel thereby being positioned in accordance with the signal impulses.

5. In a permutation code printing telegraph receiver, printing means, stop means for positioning said printing means comprising a series of rows of stops, the number of stops of each row being progressively doubled with respect to the preceding row, one row of stops being provided for each unit of a permutation code by which the receiver is to be controlled, an escapement member cooperable with said rows of stops, means to set said escapement member in accordance with said received signals, and means for imparting rotational and translational movements to said stop means to thereby bring successive rows of said stops into cooperation with said escapement member in order to position said printing means in accordance with the received signals.

6. In a selector, a shaft rotatably and translatable movable to any one of a plurality of character stop positions, a type wheel on said shaft and movable therewith, means for rotating said shaft, a projection assembly carried by said shaft, said projection assembly comprising a plurality of toothed members arranged successively along said shaft, the teeth of each member being progressively doubled with respect to the preceding member, a signal controlled escapement mechanism for controlling rotation of said projection assembly, and means for imparting translatory motion to said shaft to cause successive toothed members to cooperate with said escapement mechanism to thereby position said type wheel in accordance with signals controlling said escapement mechanism.

7. In a recorder, a rotatable shaft, means carried by said shaft having projections thereon, said means capable of rotational and translational movements, signal responsive means cooperable with said projections for effecting rotation of said first recited means, cam means for effecting translation of said first recited means cooperating with said signal responsive means to govern the ultimate position of said shaft and the projections, shift means, and means under the direct control of certain of said projections to operate said shift means.

8. In a recorder, a rotatable shaft arrestable in any one of a plurality of character stop positions, a stop unit carried by said shaft comprising a plurality of toothed elements, escapement means for arresting said shaft, means for imparting rotational and translational movements to said stop unit whereby said escapement means is adapted to cooperate with the toothed elements to determine the stop position of said stop unit, shift means, and means under the control of cer-

12

tain of said toothed elements to operate said shift means.

9. In a telegraph receiver, a case shift means, a signal responsive escapement mechanism, a rotatable and translatable projection assembly having a plurality of rows of teeth, means for rotating said projection assembly, means for imparting motion of translation to said projection assembly to enable successive rows of teeth to cooperate with said escapement mechanism to ultimately position said projection assembly, and means under the direct control of said projection assembly when ultimately positioned for operating said case shift means.

10. In a telegraph receiver, a case shift means, a rotatable projection assembly, means for imparting rotation to said projection assembly, a signal responsive escapement mechanism for controlling the rotation of said projection assembly,

20 means for imparting translatory motion to said projection assembly cooperating with said escapement mechanism to ultimately position said projection assembly, and a pair of pins associated with said case shift means under the direct control of said projection assembly when ultimately positioned for operating said case shift means.

25 11. In a telegraph printer, a type wheel positionable in either of two translatory positions, a rotatable stop unit, means for rotating said stop unit, a signal responsive means for controlling the rotation of said stop unit, said signal responsive means further determining the ultimate position of said stop unit, and means directly controlled by said stop unit and rendered operable upon the 30 ultimate position thereof in predetermined positions for positioning said type wheel in one of its two translatory positions.

35 12. In a telegraph receiver, a rotatable type wheel comprising a plurality of rows of type faces, means for moving said type wheel translatable to any one of a plurality of positions whereby each of said plurality of rows of type faces may be rendered effective, means for controlling said type wheel moving means, a rotatable projection assembly, means for imparting rotation to said projection assembly, a signal responsive mechanism for controlling the rotation of said projection assembly, means for imparting translatory motion to said projection assembly 40 cooperating with said signal responsive mechanism to ultimately position said projection assembly, and means under the direct control of said projection assembly when ultimately positioned for operating said means for controlling said type wheel moving means.

45 13. In a selector, a rotatable shaft arrestable in any one of a plurality of character stop positions, a stop unit carried by said shaft comprising a plurality of toothed elements, clutch means 50 for imparting rotation to said shaft and stop unit, a signal responsive escapement mechanism for cooperating with said stop unit to arrest the rotational movement of said shaft, means for imparting translational movement to said shaft 55 cooperating with said escapement mechanism to determine the stop position of said shaft, said clutch means tending to slip up to a predetermined amount upon initial operation, and means secured to said shaft rendered operable upon

60 slippage of said clutch means for engaging said escapement mechanism to prevent said arrest of said shaft and to thereby enable said shaft to rotate an amount commensurate with said slippage of said clutch means.

65 14. In a signal controlled selector, a rotatable

shaft, a projection assembly carried by said shaft, means for imparting rotation to said shaft, a signal controlled escapement mechanism co-operating with said projection assembly, means for imparting translational movement to said shaft cooperating with said escapement mechanism to determine a stop position of said shaft in accordance with signals controlling said escapement mechanism, said rotation imparting means tending to slip up to a predetermined amount upon initial operation, and means secured to said shaft rendered operable upon slippage of said rotation imparting means to engage said escapement mechanism to prevent stopping of rotation of said shaft by said escapement mechanism to thereby enable said shaft to rotate an amount commensurate with said slippage of said rotation imparting means.

15. In a signal controlled selector, a rotatable shaft, a projection assembly carried by said shaft, means for imparting rotation to said shaft, a signal controlled mechanism having a stop pawl and a holding pawl thereon for cooperating with said projection assembly to control the rotation of said shaft in accordance with a controlling signal, means for translatably moving said shaft cooperating with said signal controlled mechanism to determine a stop position of said shaft in accordance with the controlling signal, said rotation imparting means tending to slip up to a predetermined amount upon initial operation, and a deflector secured to said shaft rendered operable upon slippage of said rotation imparting means for deflecting said holding pawl from said projection assembly and thereby preventing stopping of rotation of said shaft by said holding pawl to thereby enable said shaft to rotate an amount commensurate with said slippage of said rotation imparting means.

16. In a signal controlled selector, a rotatable shaft, a projection assembly carried by said shaft, means for imparting rotation to said shaft, a signal controlled escapement mechanism for cooperating with said projection assembly to control the rotation of said shaft in accordance with a controlling signal, means for translatably moving said shaft cooperating with said escapement mechanism to determine a stop position of said shaft in accordance with the controlling signal, said rotation imparting means tending to slip up to a predetermined amount upon initial operation, and means secured to said shaft rendered operable upon slippage of said rotation imparting means for engaging and thereby momentarily suspending the operation of said escapement mechanism to thereby enable said shaft to

rotate an amount commensurate with said slippage of said rotation imparting means.

17. In a signal controlled selector, a rotatable shaft, a projection assembly carried by said shaft, means for imparting rotation to said shaft, a signal controlled escapement mechanism for cooperating with said projection assembly to control the rotation of said shaft, means for translatably moving said shaft cooperating with said escapement mechanism to determine a stop position of said shaft, said rotation imparting means tending to slip up to a predetermined amount upon initial operation thereby failing to immediately rotate said shaft, and a deflector secured to said shaft operative upon failure of said rotation imparting means to immediately rotate said shaft for engaging and momentarily suspending the operation of said escapement mechanism to thereby enable said shaft to rotate an amount commensurate with the slippage of said shaft upon the failure of said rotation imparting means to immediately rotate said shaft.
18. In a telegraph printer, a rotatable shaft, a stop unit on said shaft comprising a plurality of ratchet members, means for rotating said shaft, a signal controlled escapement mechanism cooperable with said stop unit, cam means for moving said shaft translatably to thereby move successive ones of said ratchet members into operative engagement with said escapement mechanism in timed relation with signal impulses controlling said escapement mechanism, whereby said escapement mechanism controls the rotation of said shaft, said shaft rotating means tending to slip up to a predetermined amount upon initial operation, and a deflector carried by said shaft for engaging said escapement mechanism between successive signal impulses and effective upon slippage of said shaft rotating means to suspend operation of said escapement mechanism to enable said shaft to rotate an amount commensurate with said slippage of said shaft rotating means.
